CLAIM

The ornamental design for a coffee grinder, as shown
and described.

DESCRIPTION

FIG. 1 is a top front perspective view of a coffee
grinder showing my new design;

FIG. 2 is a left side elevational view thereof;

FIG. 3 is a front elevational view thereof; and

FIG. 4 is a top plan view thereof.

The base of the coffee grinder is plain and unornamented.

FIG. 1

FIG. 4

FIG. 3

FIG. 2
